Patented Jan. 20, 1914.

UNITED STATES PATENT OFFICE.

FORREST E. YARIAN, OF BOURBON, INDIANA.

ATTACHMENT FOR CARRIAGE-BOOTS.

1,084,999.

Specification of Letters Patent.

Patented Jan. 20, 1914.

Application filed March 8, 1913. Serial No. 753,051.

To all whom it may concern:

Be it known that I, FORREST E. YARIAN, a citizen of the United States, residing at Bourbon, in the county of Marshall and State of Indiana, have invented certain new and useful Improvements in Attachments for Carriage-Boots, of which the following is a specification, reference being had to the accompanying drawings.

10 This invention relates to improvements in holder attachments for carriage boots, and an object thereof is the provision of an attachment which will securely hold the boot of a carriage or other vehicle in either an 15 open or a closed position.

Another object of this invention is the provision of an attachment of this character, which comprises a pair of arms which are pivotally connected together at one of 20 their respective ends, the opposite end of one of the arms being pivotally connected to the under face of the carriage boot, the opposite end of the other arm being pivotally connected to the floor of the carriage, 25 and a spring connected to the arms near their pivotal point to hold the arms in either a closed or open position, and thereby hold the carriage boot either in open or closed position.

30 With these and other objects in view, my invention consists in certain novel constructions, combinations, and arrangements of parts, to be hereinafter more fully described, claimed and illustrated in the accompanying 35 drawing, in which—

Figure 1 is a side elevation of my attachment showing it applied. Fig. 2 is a fragmentary edge view showing the arms in extended position. Fig. 3 is a side elevation 40 of one of the arms, and Fig. 4 is a fragmentary side elevation showing the arms in extended position.

The attachments are preferably arranged in the carriage box at the opposite sides 45 thereof, and each attachment comprises a pair of substantially counterpart upper and lower arms designated at 1 and 2, respectively, the arms being pivotally connected together at one end, as at 3. The arms 1 and 50 2 extend forwardly in the carriage box, and counterpart angle plates or brackets 4 and 5 are pivotally secured to the upper arm 2 and the lower arm 1 respectively. Each of the plates 4 comprise a vertically extending

flange 6 which is provided with a central 55 opening 7 having pivots seated therein whereby the plates may be pivotally secured to the ends of the arms opposite to the pivot which unites them, the plates each being provided with a horizontal flange 8, which 60 is formed with suitable openings 9 whereby the plate 4 may be secured to the under face of the carriage boot, and the plate 5 may be secured to the floor of the carriage. The arm 1 is provided with an upwardly extending 65 offset 10 which is bent at its extremity at right angles to the body portion of the arm 2, as at 11, and the arm 2 is provided with a downwardly extending offset 12 near the pivot point 3, the offset 12 being disposed in vertical alinement with the offset 10, and being provided with a laterally extending apertured ear 13 at its extremity. Connected to the angular apertured ears 11 and 13 are the opposite ends of a coiled contractile spring 14, the spring being adapted 70 to maintain the arms in either closed or open position. Formed on the arm 2 is a laterally extending lug 15 which is adapted to engage the edge of the arm 1 to limit the swing 75 of the arms on the pivot 3.

The operation of my device is as follows: In the practical use thereof, one of the holder attachments is arranged within the vehicle box on each side thereof, so that the 80 pivotal point 3 is disposed toward the forward end of the vehicle. The angle plates 4 and 5 are secured to the boot and floor of the carriage respectively, and when the arms are in closed position, the spring 14 is disposed rearwardly of the pivotal point of the arms. When the boot is raised, it will be seen that the spring 14 is moved forward 85 relative to the pivotal point 3, so that the spring now exerts a pull which tends to bring the elements 11 and 13 into closer 90 proximity, and holds the arms in open position, as illustrated in dotted lines in Fig. 1, so as to hold the boot in open position.

Having thus described my invention what 100 I desire to claim and secure by Letters Patent is:

In combination with a carriage and a boot connected thereto, a pair of substantially counterpart brackets secured respectively on 105 the boot and the bottom of the box in vertical alinement, a pair of substantially counterpart arms pivotally connected together at

one end and each having an end pivotally connected to one of said brackets, each said arm being provided with a lateral apertured extension adjacent to the end at which the 5 arms are pivotally connected, and a contractile spring having its ends connected to the respective lateral extensions and being so positioned relative to the arms as to have

its intermediate portion unobstructed when such arms are moved upon their pivots.

10

In testimony whereof I hereunto affix my signature in the presence of two witnesses.

FORREST E. YARIAN.

Witnesses:

WILLIAM A. YARIAN,
BRODIE W. PARKS.
